(57) **CLAIM**

The ornamental design for an electrician's combination wire-working pliers, as shown and described.

DESCRIPTION

FIG. 1 is a front, top, left perspective view of an electrician's combination wire-working pliers showing the new design; FIG. 2 is a rear, top, right perspective view of the electrician's combination wire-working pliers shown in FIG. 1; FIG. 3 is a top view of the electrician's combination wire-working pliers shown in FIG. 1; FIG. 4 is a left-side view of the electrician's combination wire-working pliers shown in FIG. 1; FIG. 5 is a front view of the electrician's combination wire-working pliers shown in FIG. 1; FIG. 6 is a right-side view of the electrician's combination wire-working pliers shown in FIG. 1; FIG. 7 is a rear view of the electrician's combination wire-working pliers shown in FIG. 1; and, FIG. 8 is a bottom view of the electrician's combination wire-working pliers shown in FIG. 1. The broken lines indicate unclaimed portions of the article and form no part of the claimed design.

1 Claim, 3 Drawing Sheets
